UNITED STATES PATENT OFFICE.

FLAVIUS W. SHELLABARGER, OF MIAMI COUNTY, ASSIGNOR TO THE
IRON MONITOR WIND ENGINE AND MANUFACTURING COMPANY,
OF TROY, OHIO.

WIND-ENGINE.

SPECIFICATION forming part of Letters Patent No. 257,835, dated May 9, 1882.

Application filed March 10, 1881. (No model.)

To all whom it may concern:

Be it known that I, FLAVIUS W. SHELLABARGER, of the county of Miami, in the State of Ohio, have invented a new and useful Improvement in Wind-Engines, of which the following is a full, clear, and concise specification.

My invention relates to that class of wind-engines in which the wheel is reversed—*i. e.*, placed with face side inward toward the derrick—the object being to have the wind operate upon the governor before it reaches the wheel, so as to throw the latter out of the wind or out of gear in advance of the action of the wind upon its vanes or sails.

My invention relates to certain improvements upon my patent of March 19, 1878, whereby it is rendered more complete and effective in its operation and giving in proportion to its size a greater amount of useful effect.

Figure 1 is a view of the improved spider or runner, the wheel-hub, and two of the arms or spokes, with their vanes pivoted thereon. Fig. 2 is a longitudinal sectional view of the main shaft and a vertical section of the wheel-hub and spider and connecting-rod, and a view of the eccentric and the main fork or bracket. Fig. 3 is a cross-section through line 1, Fig. 2, with a view of the governor-vane also. Fig. 4 is a side view of my invention, showing the action of the governor-vane in dotted lines.

My improvement pertains more particularly to those parts which are exhibited in the annexed drawings.

A is the wheel; B, the spider or runner, which in this engine is placed upon the hollow shaft E in rear of the wheel A, upon the extreme end of the same. (See Fig. 2.)

C is the bracket or main fork, which supports the main shaft and wheel.

The eccentric D is mounted centrally upon the main shaft, directly over the pump. It is cased with a circular box or casing, d, which extends partially over the sides, as shown in the dotted circular line, Fig. 3, is in two parts, 45 and riveted together through projecting ears on the periphery of the contiguous halves. An arm, d', extends from the lower rear edge downward, and is pivoted to pump-lever m'

near its inner end. This lever is pivoted at its outer end to a side arm, m, of the main fork 50 at its extremity. It has a spherical case, l, on its inner end, in which is a ball, n', with a vertical hole through it, in which the pump-rod is suspended. As the lever m' is operated through its connection with the eccentric, the ball-joint 55 allows the rod to maintain its verticality when in motion. In Fig. 2 the ball and shell are shown in cross-section, and in Fig. 3 with a half-section broken off and removed.

A connecting-rod extends from the governor 60 on the front end of the engine to the spider, which operates the wheel-vanes through the main shaft E. The section e' of this rod reaches from the extreme rear end to the front of the bracket, and has a ball, g', formed on its front 65 end, which operates in a spherical case, g, on the rear of the connecting-sleeve i. This sleeve is pierced centrally at the front end with a hole smaller than its internal diameter, and into this hole the rod f (connecting it with the rock-shaft G, which supports the governor-vane) is inserted and secured by the inner and outer nuts, i' and i'', on its threaded end. (See Fig. 2.)

The front end of rod f is connected flexibly with the end of an upward and rearwardly 75 curved arm, p, of the rock-shaft. The rock-shaft is pivoted in the front ends of the horizontal bars o', which extend forward from the front limb, 3, of the bracket. (See Figs. 2, 3, and 4.)

The rod f', which supports the governor-vane F, is square, is set in the rock-shaft with its angles in line with the main shaft to give it additional strength. The top where the vane fits against it is twisted to present one side to 85 the face of the vane, as shown in Fig. 3.

The operation of the governor-vane is the same as that in my windmill patented March 19, 1878—*i. e.*, the vanes of the wheel are thrown out of the wind by the governor-vane 90 being inclined toward the wheel. It, however, differs in the vane F being made of a single piece rigidly attached.

A right-angled bar, k, pivoted at the angle to one side of the front limb, 3, connects the 95 governor-rod f'' with a wire, h, attached to its

vertical limb, and a chain depending from its horizontal limb to the foot of the derrick, through the eyes *e e e* in the bracket and its stem, allows the governor-vane to be operated 5 by hand.

The eyes *e* are cast on the inner front side of the hollow of the bracket. (See Fig. 2, which shows a part broken out to exhibit them.) To allow the wheel to turn quickly "into wind," 10 the spindle *S* of the turn-table has a semi-cylindrical concave niche in its front and rear side just under the shoulder of the bracket. In these niches a cylindrical friction-roller is pivoted vertically to free the stem at these two points 15 from contact with the interior surface of the socket. The wheel-vanes *a* are oblong, with the exterior end rounded and the outer angle slightly curved. They are of light sheet metal, strengthened by a border of narrow strap-iron, 20 *a''*, riveted upon the face.

Arms *b*, of Y shape, made of malleable iron, and cast in a single piece with the cross-bar *b''* and the eye *c''*, (through which the wheel-arm *a'* extends,) are riveted across the inner 25 edge or heel of the wing-vanes, so as to strengthen this part. The stem of the Y-shaped piece *b* terminates in a slotted head, and this is connected with the ends of the spokes of the spider by links *c*. These latter are short straight 30 rods with an eye in each end. A pivot-bolt connects one end with the arm *b* and the other end is slipped over a tangential journal, *c'*, on the tip of the spider-arm. Each vane is in this manner connected to the spider-arm next 35 in rear of it, as seen in Fig. 1. The terminal *c'* has a broad shoulder like a large rivet-head.

It will be noticed by reference to Fig. 1 that the diameter of the spider *B* is large in proportion to the size of the wheel-vanes, the latter being comparatively short. The spider fills the entire open space from the hub to the heel of the wing-vanes, giving increased leverage and easier operation to the governor. The spokes *a'* of the wheel terminate before reaching 45 the ends of the wheel-vanes, which have an oval hole, *j*, at this point cut through them, to allow the straining-rod *o* to connect with the thimble or cap on the ends of the spokes, and to give room at this point for the operation of 50 the vane. Braces of rod-iron *r* extend from the heel-thimble *c''*, diverging toward the extremity of the wing-vane till they reach points at each edge opposite to the end of the wheel-arm, where they are fastened. They greatly 55 strengthen the wheel-vanes, and prevent their twisting from a sudden gust of wind.

I claim as my improvement—

1. In wind-engines having the governor so

placed as to face the wind, the combination of the spider *B* on the rear end of the hollow 60 shaft *E*, having the terminals *c'*, by which the several spokes of the spider are each connected with the wheel-vane next in advance of it, by the longitudinal movement of which the vanes are turned into or out of wind, substantially 65 as shown, for the purpose set forth.

2. Vane-arm *b*, having cross-bar *b''* and thimble *c''*, and cast in a single piece, whereby the wing-vane is strengthened at the point where it is connected with the arm or spoke of the 70 spider *B*, as shown.

3. In wind-engines, the combination of the centrally-pivoted wind-vanes *a*, strengthened at their edges by a border of strap-iron, with the thimble *c''* and brace-rods *r*, attached thereto and to the strengthened edges, as shown and described. 75

4. In a wind-engine having its wheel connected with the governor through a hollow main shaft by a rod or its equivalent, the combination of a ball-and-socket joint-piece and adjusting-nuts with its connecting-sections, substantially as herein shown and specified. 80

5. In a wind-engine, the combination of the arm *b*, cross-bar *b''*, and thimble *c''*, formed in 85 a single piece, with the vane *a*, provided with centrally-secured brace-rods *r* and strengthening-binding *a''*, as shown and described.

6. The wheel-vane *a*, formed with a hole 90 therein, in combination with the cap or thimble *j* and brace-rods *o*, substantially as shown and described.

7. The eccentric strap *d*, having the arm *d'*, extending obliquely downward therefrom, in combination with lever *m'* and arm *m* and the 95 ball-and-socket end joint, *n' l*, as shown and described.

8. In combination with fork *C* and the supporting column, the hollow stem *S*, having the friction-rollers *n*, pivoted in niches formed in 100 its sides, as shown and described.

9. In a wind-engine, the vibrating governor having vane *F*, twisted stem *f'*, rock-shaft *G*, rod *h*, and bell-crank *k* and chain, in combination with arm *p*, rod *f*, coupling *g g'*, rod *e*, hollow shaft *b'*, and spider *B*, as shown and described. 105

10. The combination, with the automatic rock-shaft *G*, curved arm *p*, and rod *f*, of the flexible coupling *g g'*, rod *e'*, hollow shaft *b'*, and spider *B*, as shown and described. 110
